CHARCOAL GRILL

William S. Hoebel, Rte. 2, Box 43, Prairie View, Ill.

Filed Jan. 13, 1959, Ser. No. 54,156

Term of patent 14 years

(Cl. D81—10)

Fig. 1 is a front perspective view of a charcoal grill showing my new design with handles in carrying position; and

Fig. 2 is a similar perspective view taken from the opposite side with the handles disposed to support the grill.

The rear and bottom of the grill are plain as indicated in Figs. 1 and 2.

I claim:

The ornamental design for a charcoal grill, as shown and described.
